United States Patent Office

Des. 211,018

Patented May 14, 1968

211,018

CHAIR OR SIMILAR ARTICLE

David D. Granger, Conover, N.C., assignor to Maxwell Royal Chair Co., Hickory, N.C., a corporation of North Carolina

Filed May 15, 1967, Ser. No. 7,120

Term of patent 14 years

(Cl. D15—1)

FIGURE 1 is a front perspective view of a chair or similar article showing my new design with portions thereof broken away to indicate indeterminate length;

The dominant features of my design reside in those portions shown in full lines.

I claim:

The ornamental design for a chair or similar article, as shown and described.
